UNITED STATES PATENT OFFICE.

GUSTAV BLUMBERG AND JOHN A. BUTKUS, OF BALTIMORE, MARYLAND.

ELECTRIC CLOCK.

1,244,164.

Specification of Letters Patent. Patented Oct. 23, 1917.

Application filed October 13, 1915. Serial No. 55,682.

To all whom it may concern:

Be it known that we, GUSTAV BLUMBERG and JOHN A. BUTKUS, citizens of the United States, residing at Baltimore, in the State of Maryland, have invented certain new and useful Improvements in Electric Clocks; and we do hereby declare the following to be a full, clear, and exact description of the invention, such as will enable others skilled in the art to which it appertains to make and use the same.

Our invention relates to electric clocks, such as are complete in themselves and require no connection with a central clock or an outside source of electricity. The object of our invention is to produce an electric clock which shall be entirely devoid of springs in the time train and which shall be simple, cheap, reliable and in which the electrical mechanism can be quickly removed from the time mechanism for examination, renewal or repairs.

In the drawings:

Figure 1, is a front view of our improved clock showing the case, dial and hands;

Fig. 2, is a side view thereof;

Fig. 3, is a front view of the time train and the electrical mechanism, certain features of the time train being omitted;

Fig. 4, is a view of the electrical mechanism looking in the direction of the arrow 4 in Fig. 3;

Fig. 5, is an enlarged sectional view of our improved clock along the line 5—5 of Fig. 1 looking in the direction of the arrows; certain features of the time train being omitted;

Fig. 6, is an enlarged sectional view of our improved clock along the line 6—6 of Fig. 1 looking in the direction of the arrows; certain features of the time train and electrical mechanism being omitted; and

Fig. 7, is a diagram of connections of our improved clock.

Fig. 8 is a detailed perspective view of some of the working parts of our improved electric clock, hereinafter referred to.

In the drawings:

10 represents a base board of our improved clock to which two side pieces 11—11 are secured in any approved manner. The side pieces 11—11 are connected at their tops by the baton 12. A door 13 is hinged as at

14 to the right hand side 11 and is provided with a lock having a key hole 15 for locking the other side of the door 13 to the left hand side 11. The door 13 is provided with a circular opening 16, which is closed by a glass plate 17. The sides 11—11 are provided with grooves in which slide the rabbits 18—18 formed on the back board 19. The back board 19 is secured to the top 20 and the baton 21 is glued in the angle between the back board 19 and the top 20 to strengthen the juncture between said parts. The top 20 is adapted to rest across the top ends of the sides 11—11, and the top of the door 13. A door 22 is hinged as at 23—23 to the base board 10 and is provided at its upper edge with a rabbet 24 which is overlaid by the rabbet 25 on the lower edge of the door 13, so that when the latter door is locked it will also secure the door 22. A board 26 extends between the sides 11—11 and between the said board and the base board 10 partitions such as at 27 are secured. The board 26 and partitions 27 do not extend to the back board 19 but terminate at sufficient distance therefrom to permit the passage of the connectors 28 when the back board 19 is removed from the case as hereinafter described.

There are two connectors 28—28 for each battery 29 employed, and there may be as many batteries such as 29 as it is desirable to use. The batteries 29 are provided with two spring clips such as 30 for each terminal of each battery and said spring clips are so located so that when each battery is pushed into the compartment formed by the partitions 27, said clips 30 will make proper contact with the connectors 28 as shown in Fig. 6.

Screws such as 31—31—31 secure the mechanism of our improved clock to the back board 19.

The mechanism of our improved clock consists of two plates 32 and 33 which are formed with a circular rim and a five pointed star such as 34 formed integrally therewith. These plates are kept in proper relation to each other by posts such as 35 and in the proper relation to the back board 19 by posts such as 36.

The plates 32 and 33 support an ordinary

time train provided with hands such as 37-37 and a dial such as 38. It also has an ordinary pendulum wire such as 87 to which is attached a pendulum not shown.

5 All parts of the time train being old and well known will not be further illustrated or described.

A plate such as 39 is secured at the rear of the plate 33 by the following instrumentalities. Posts such as 40-40 are riveted to the plate 39 and the front ends of said posts are reduced in diameter as at 41-41 and pass through holes provided in the plate 33. A cotter pin such as 42 is passed through 10 the portions 41-41 on the front side of the plate 33 and thus keeps the plate 39 in proper relation to the plate 33 as shown in Figs. 3, 5 and 6.

15 The plate 39 extends toward the right, (as shown in Fig. 3), and is provided with a downward extension 43 to which is secured the solenoid 44.

The solenoid 44 is formed with two insulating end pieces 45 provided with a central 20 hole and joined together by an insulating tube not shown. The ends 45-45 are secured to the extension 43 by the screws 46-46. The solenoid 44 is wound with a plurality of turns of wire of any suitable 25 size and the ends 47-47 of said winding are brought through the lower end piece 45 of the solenoid.

30 A condenser consisting of two plates 48 and 49, (see Fig. 7), is wound in cylindrical form, as shown at 50 in Figs. 3 and 5, and provided with terminals 51 and 52 by which the condenser is secured to the ends 45-45 by the screws 53-53.

A core such as 54, preferably formed of 35 soft iron or steel, moves freely in the tube joining the ends 45-45 of the solenoid. The upper end of the core 54 is provided with a threaded hole such as 55 in which is screwed the threaded wire 56. The wire 40 56 is thus threaded in the core 54 so that said core can be adjusted with relation to the solenoid 44. The means for adjusting the position of the core 54 upon the wire 56 is provided so that the core 54 can be 45 adjusted to work within the range of maximum force of the solenoid 44. The upper end of the wire 56 is provided with a hole in which fits loosely a shoulder portion provided on the screw 57. The inner end of 50 the screw 57 is threaded as at 58 and is screwed into one end of the link 59. The other end of the link 59 is provided with a hole which works freely on a shoulder provided on a screw 60 and the inner end 55 of the screw 60 is threaded as at 61, the threaded portion 61 being screwed in to the lever 62.

The lever 62 is revolvably mounted on one of the pintles such as 63 of the time train.

The pindle 63 has rigidly attached thereto 65 a ratchet wheel 64, and a pawl 65 pivotally mounted on the lever 62 is kept in engagement with the ratchet wheel 64 by the spring 66.

The teeth of the ratchet wheel 64 are related to the pawl 65 and lever 62, so that when the parts are in the position shown in Fig. 3, the weight of the core 54, wire 56, link 59 and screws 57 and 60 with the weight of the overhanging portion of the lever 62, 70 will move the ratchet wheel 64 in the direction of the arrow 67 and thus move the whole time train.

75 It is evident that when the core 54 has reached the limit of its downward movement it must be restored to the position shown in Fig. 3 in order to provide for the continuous movement of the time train. The instrumentalities by which we accomplish the intermittent restoration of the core 80 54 to the position shown in Fig. 3, will now be described.

85 A five pointed star wheel 68 is revolvably mounted in any approved manner upon the plate 39 and a five pointed ratchet wheel 90 such as 69 is rigidly secured to the star wheel 68, the axes of both wheels being in line. The relative position of the points of the star wheel 68 and the points of the ratchet wheel 69 are shown in Fig. 3, and 95 a spring such as 70 is provided to keep said star and ratchet wheels in the position shown in said figure.

99 The spring 70 is secured in the post 71 and the latter is mounted on the plate 39. 100 The spring 70 is provided with two depressions 72 and 73, the former of which embraces one of the points of the ratchet wheel 69 when the end 74 contacts with the point of the adjacent tooth of said ratchet wheel. 105 This action of the depression 72 and end 74 of the spring 70 upon the points of two adjacent teeth of the ratchet wheel 69 holds said ratchet wheel and star wheel 68 in the positions shown in Fig. 3.

110 A small bracket such as 75 is secured to the lever 62. This bracket is provided with a slot and in said slot the pawl 76 is pivotally mounted on a pin 77. The pawl 76 has a weighted end 78 which retains it in the 115 position shown in Figs. 3, 4 and 5 so that the inner end 79 thereof shall overlie one point of the star wheel 68 (see Fig. 5).

120 Another bracket 80 is secured to the lever 62. Said bracket is provided with a slot and in said slot the pawl 81 is pivotally mounted on the pin 82. The inner end 83 of the pawl 81 is so placed that it shall underlie one of the points of the star wheel as 125 shown in Figs. 3, 4 and 5.

The pawls 76 and 81 are provided with suitable stops in any approved manner so that the point 79 of the former can move

downwardly from the position shown in Fig. 4 but not upwardly from said position, and so that the point 83 of the latter can move upwardly from the position shown in Fig. 4 but not downwardly therefrom.

A post such as 84 is mounted on the plate 39 but insulated therefrom by insulation such as 85. To the post 84 is secured one end of the spring 86, the free end of which is located to be touched by the ends of the teeth of the star wheel 68.

The electrical connections of our improved clock are as follows:

One terminal of the battery 29 is connected with the spring 86, the other terminal of said battery is connected with one terminal of the solenoid 44 and the other terminal of said solenoid is connected with the plate 39 which is in electrical connection with the star wheel 68. One plate 49 of the condenser is connected with the plate 39 by which said plate of the condenser is placed in electrical connection with one terminal of the solenoid 44 and the star wheel 68, and the other plate 48 of said condenser is connected with the spring 86 and one terminal of the battery. The batteries 29 are connected together by wires joining the proper connectors 28 and of the two of said connectors which are not thus joined, one is connected to the solenoid 44 and the other to the spring 86.

The operation of our electrical clock is as follows:

The parts being in the positions shown in Fig. 3, the weight of the core 54 and other parts supported by the lever 62 will act to move the ratchet wheel 64 in the direction of the arrow 67 and thus move the time train 40 and hands 37 at a rate determined by the oscillation of the pendulum attached to the wire 87.

The lever 62 and attached parts will continue to move downwardly and the end 79 of the pawl 76 will move the tooth 88 of the star wheel 68 downwardly, this motion will continue until the point of the tooth 89 of the ratchet wheel 69 enters the depression 73 of the spring 70 and then the pressure of said spring against the point of the tooth 89 will continue the upward movement of said tooth and bring the point of the tooth 90 of the star wheel 68 into contact with the end of the spring 86 as shown dotted in Fig. 7. During the upward movement of the tooth 90, (see Fig. 7) it will strike the inner end 83 of the pawl 81 and move said point 83 upwardly until said tooth 90 passes the end 83 of the pawl 81, then said pawl 60 will drop in to the same relation to the bracket 80 as shown in Fig. 4, thus putting the point 83 of the pawl 81 under the tooth 90 of the star wheel 68. When the tooth 90 makes contact with the spring 86, a current

of electricity flows through the solenoid 44, 68 the core 54 is then attracted upwardly, this moves the lever 62 upwardly and the point 83 of the pawl 81 being under the tooth 90 as just described, moves said tooth upwardly and from contact with the spring 86, 70 the current of electricity ceases to flow, the upward motion of the core 54 is terminated and the spring 70 holds the star wheel 68 in the position shown in Fig. 3 as before described.

During the upward motion of the tooth 90 caused by the point 83 of the pawl 81, the tooth 91 of the star wheel 68 will strike the end 79 of the pawl 76 and move said end downwardly until said tooth 91 releases said end 79. The weighted portion 78 of the pawl 76 will then bring the end 79 into the position shown in Fig. 4, so that it can repeat the same function with reference to the tooth 91 as has just been described with reference to the tooth 90.

Hence it is evident that each time the core 54 reaches its lowest position, a tooth of the star wheel 68 makes contact with the spring 86, the core 54 is attracted upwardly, said contact is broken and the pawl 65 co-acts with one of the teeth of the ratchet wheel 64 to lock said ratchet wheel and lever 62 together, so that the weight of the core 54, lever 62 and attached parts will continuously move the time train.

When the tooth 90 is moved from contact with the spring 86, the extra current of self induction will accumulate on the plates of the condenser and hence obviate arcing between the tooth 90 and spring 86.

When the time train or the electrical mechanism or both are to be removed from the casing for examination, renewals or repairs, the door 13 is to be opened, the door 22 turned downwardly, and the batteries 29 pulled out until the clips 30 are free from the connectors 28. The top 20 and the back board 19 with the attached time train and electrical mechanism can then be raised vertically from the sides 11-11.

If it is desired to work on the electrical mechanism, or to place a new electrical mechanism in combination with the time train, this can readily be effected by removing the cotter pin 42 and moving the plate 39 backwardly until the reduced portions 41 of the studs 40 are clear of the plate 33.

It is also evident that while the door 22 is opened, that new batteries can be readily placed in the compartments formed by the partitions 27. One of the battery terminals is screwed to the plate 39 in any approved manner and the other battery terminal is attached to the insulated post 84 in any approved manner.

When it is desired to adjust the relative positions of the solenoid 44 and solenoid

core 54, this is readily effected by turning the latter in either direction, which causes the core 54 to move upwardly or downwardly with reference to the threaded 5 wire 56.

When it is desired to adjust the normal position of the star wheel 68, this is effected by loosening the screw 92 and moving the spring 70 in the desired direction.

10 When it is desired to adjust the position at which the tooth of the star wheel 68 breaks contact with the spring 86, this is effected by loosening the screw 93 and moving the spring 86 either upwardly or down- 15 wardly.

We claim:—

1. The combination with a lever, of a solenoid core, a solenoid, a star wheel, a pawl operated by said lever to move said star 20 wheel in one direction, a second pawl operated by said lever to move said star wheel in the opposite direction, a ratchet wheel mounted on said star wheel and a spring acting on said ratchet wheel to move said 25 star wheel slightly after it has been moved by the first of said pawls, and to hold said star wheel in the position into which it is moved by the second of said pawls.

2. The combination with a lever, of a solenoid core, a solenoid, a star wheel, a pawl operated by said lever to move said star wheel in one direction, a second pawl operated by said lever to move said star wheel in the opposite direction, a source of elec- 35 tricity, a circuit including said source of

electricity and said solenoid and having one terminal connected to said star wheel, and a spring connected to the other terminal of said circuit and adapted to make and break contact with the points of said star wheel. 40

3. The combination with a lever, of a solenoid core, a solenoid, a star wheel, dual means carried by said lever for moving said star wheel in the same direction, and a spring adapted to make and break contact 45 with the points of said star wheel.

4. The combination with a lever, of a solenoid core, a solenoid, a star wheel, means carried by said lever for moving said star wheel in opposite directions, a spring 50 adapted to make and break contact with the points of said star wheel, a ratchet wheel carried by said star wheel, and a spring bearing against the points of said ratchet wheel. 55

5. The combination with a lever, of a solenoid core, a solenoid, a star wheel, means carried by said lever for moving said star wheel in opposite directions, a spring adapted to make and break contact with the 60 points of said star wheel, a ratchet wheel carried by said star wheel, a spring bearing against the points of said ratchet wheel, and means for adjusting the relative positions of said last named spring and said ratchet 65 wheel.

In testimony whereof we affix our signatures.

GUSTAV BLUMBERG.
JOHN A. BUTKUS.
